2,371,340

TORPEDOPROOF BATTLESHIP

Alexander D. Masloff, New York, N. Y., assignor
of sixty one-hundredths to George A. Rubisow,
New York, N. Y.

Application July 27, 1940, Serial No. 347,956

7 Claims. (Cl. 114—68)

It is known that modern armored ships, in particular, battleships, dreadnaughts, destroyers, and cruisers, are provided with two boards or walls, the outer board or wall being constructed at a distance from the inner board or wall, and various chambers and separating bulkheads—vertical, horizontal and at an angle are now utilized in order to divide the free space between the outer and inner boards into small chambers or sections so that if a torpedo explodes only some of these sections will be damaged and flooded. However, none of these known arrangements are adequate against fire, nor do they offer satisfactory protection against torpedos, mines or shells.

This invention relates to a new construction of the inner and outer boards which render a ship torpedo-proof or substantially torpedo-proof. Furthermore, this new construction as described in this specification, is more economical and simpler in its design and nature.

The main defect of present-existing constructions consists in that the separations and bulkheads, instead of permitting free escape of the exploding gases, serve, in fact, as an obstacle, thereby increasing the force of the explosion due to the known fact that the greatest destruction occurs, or tends to occur where the resistance is the greatest. Hence, each explosion destroys adjacent cells or chambers or sections and spreads in all directions.

The invention herein described provides means to render ships entirely or substantially torpedo-proof, and considerably diminish the destructive efficiency of exploded torpedos, mines, shells and the like.

One aspect of this invention consists in providing a plurality of special safety-sections in the free air-space formed between the two boards of the ship, permitting free escape of the exploded gases from such safety section or sections where the explosion has occurred, bettering such escape by especially provided trap-doors. The outer board may be made considerably thinner than the inner board and it may be placed at a sufficient distance from the inner one to create as much free air-space as deemed necessary. Such construction will permit the explosion of the torpedo, mine or shell, when hitting the outer board, and prevent the exploded gases from destroying the inner board, inasmuch as the free air-space greatly amortises and disperses them, and a relatively small part of the explosion will be received by the inner board.

In the drawing, wherein like reference charac-

ters refer to like parts throughout the several views, diagrammatical schemes of different arrangements according to this invention are shown, and also, by way of example, several forms of execution of this invention.

Figure 1 represents a diagrammatical, longitudinal side-view of a part of a ship partly in cross-section with parts progressively broken out.

Figure 2 is a plan-view of Figure 1, with parts broken out.

Figure 3 is a cross-sectional view of Figure 1.

Figure 4 is a schematical view of trap-door and mechanism to operate same.

Figure 5 is a plan-view of a part of the mechanism to operate the trap-door shown on Figure 4.

Figure 6 is another diagrammatical, longitudinal side-view of a ship with parts broken out.

One aspect of this invention, as shown in Figures 1, 2 and 3, consists in removing or eliminating all horizontal and/or all inclined (in respect to the longitudinal axle of the ship) separation walls or bulkheads from the already existing construction, preferably from battleships, in which they were previously provided, leaving only vertical bulkheads or vertical separation walls.

Another aspect of this invention consists in designing and building new ships, preferably battleships, destroyers, dreadnaughts, cruisers, and even submarines and other ships, so that no horizontal or inclined (in respect to the longitudinal axle of the ship) bulkheads or separation walls are provided, only vertical bulkheads or walls such as 10, 11, 12, 13, 14, 50, 51, 52, and 53 as shown on Figures 1, 2, 3 and 6.

Figure 1 represents schematically: from left to right the outer board 21; in dotted lines, the vertical or substantially vertical beams 15 and 16 and the vertical bulkheads or separation walls 10; the outer board 21 broken out and vertical beams 17—18 and vertical bulkheads or separation walls 11 and 12; also vertical beams or substantially vertical beams as 17—18 broken out; horizontal beams 30a, 30b, 30c, 30d in cross-section; and vertical bulkheads or separation walls 13, 14 (14₁—14₂) shown in cross-section.

It should be noted that bulkheads 10, 11, 12, 13, 14 (14₁—14₂) are shown for purposes of example, being of different heights. The bulkheads, 10, 11, 12 start from the bottom K and end at the upper deck U. Bulkheads 13 and 14₁—14₂ are shown slightly over the water-line W, and bulkhead 14 is shown reaching to the A deck. This invention does not limit any desirable combination of heights for the bulkheads and the given example does not limit it in any way. The free air-spaces

between the bulk-heads 10—11, or 11—12, or 12—13, or 13—14, etc. . . . will be called "safety-sections." All such safety-sections communicate with the remaining undivided partition of the free air-space M.

In order to provide a rigid structure, the outer board 21 is affixed to the inner board 22, Figures 1, 2, 3, or to the body of the ship through the intermediary of various horizontal or substantially horizontal traverses 30, 31, 32, as shown on Figures 1, 2 and 3.

On the outer ends of such beams, for instance, 30a, 30b, 30c, 30d, etc. . . . is generally, but not necessarily, provided an assembly-beam or the like, such as 15, 16, 17, 18, Figure 1, or 19, Figure 2, or 23, Figure 3, which should preferably follow the contour of the outer board 21. Each such assembly-beam may consist of one single rigid beam from upper deck U to the bottom K, or may be composed of one or more parts, i. e., for instance: 24, 25, 26 may be made as one rigid part of a beam, and 27 and 28 may be made as another rigid part of the same beam, such variation to be in accordance with the construction desired.

The vertical assembly-beams 15, 16, 19 and 20, as shown by way of example on Figures 1, 2, and 3, may be placed one in respect to the other at any desirable distance.

The horizontal beams 10, 11, 12, 13, 14 should preferably be perpendicular in respect to the inner and/or outer boards, however, beams at any angle in respect to the said boards, and in one or more planes, straight and/or curved, may be employed.

The main aspect of this invention consists in providing a construction of a ship having the outer board and the inner board comprising:

(1) A sufficiently great distance between the inner board 21 and the outer board 22, Figs. 1, 2 and 3, so that a sufficiently large free air-space with atmosphere-air is obtained.

(2) Said free air-space to be divided only by a plurality of preferably vertical or substantially vertical bulkheads or separation walls, 10, 11, 12, 13, 14.

(3) Said bulkheads (10, 11, 12, 13, 14), beginning from the bottom K or substantially the bottom K of the free air-space, and ending preferably slightly above the water-line W.

In ships of the types described herein, having five decks—an upper deck U and four decks A, B, C, and D as shown by way of example on Figures 1, 2 and 3, then the preferred construction according to this invention should all have bulkheads 10, 11, 12, 13, 14 of preferably the same height as 13 and (14₁—14₂). Such arrangement will provide a very big free air-space from the bottom K of the ship up to the top point T of 13 or of 14₁—14₂. All vertical bulkheads 10, 11, 12, 13, 14 (14₁—14₂), when of the same heights (or substantially the same heights), as for instance, the height T of 13, will form a line P₁—P₂ as shown in dotted lines, which line hereinafter will be called bulkhead top-line.

Another feature of the main aspect of this invention consists in constructing the bulkhead top-line passing substantially parallel to the A deck forming a common partition of free air-space M₃, Figure 3. Still another feature consists in having the bulkhead top-line reach the upper deck U. This construction thus provides a plurality of safety-sections which do not inter-communicate, inasmuch as, in a construction of this kind, there is no common partition of free air-space.

In the case where the bulkhead top-line passes through P—P or P₁—P₁, there should always be provided a common partition of free air-space M, Figures 1 and 3, which considerably amortizes the destructive effect of the exploded gases.

For security against rolling, the bulkhead top-line P₁—P₁ should be so placed that the safety-partitions will not be flooded through the common partition of the free air-space, in the event that one or more of the said safety-partitions are flooded due to the ship's rolling.

It is also recommended that the P₁—P₁ line be of such a character that there will be no danger of flooding through the common partition of the free air-space M in the case of pitching. This is easily achieved by an appropriate choice of P₁—P₁, as, for instance, a curved P₂—P₂ rising to the bow and stern of the ship.

P—P may also be constructed in the form of a curve, P₃—P₃ which will be useful if the bulkhead top-line P₃—P₃ in T₃ approaches the water-line at chosen intervals close enough in T and the neighboring bulkhead-top T₃ is sufficiently above the water-line, or may even be as high as deck A or U, thus reassuring the security against flooding of the neighboring safety-sections.

In such a construction, should a torpedo or mine hit the ship somewhere at point "X," Figure 1, then the exploded gases will expand in the free air-space between 13, 14 and when they reach the bulkhead top-line P₁—P₂ will expand throughout the free air-space left and right from the top T of the bulkhead 13. It must be emphasized that horizontal bulkheads or walls or decks, in accordance with this invention, are not to be provided between the inner and outer boards, so that the exploded gases can expand and meet with no obstacle on their way up or down.

Even should it come about that the explosion in "X" demolishes bulkhead 14, only the compartment between 13 and 14₁—14₂ will be flooded by water. Due to the bulkhead top-line being raised sufficiently above the water-line W, the damaging and flooding of the compartments, for example, the compartments between 13—14 (14₁—14₂) will neither prove dangerous nor fatal for the ship.

As yet, no battleships or other ships used for military purposes, have been designed or executed possessing the features of the said main aspect of the invention described herein.

This description of the main aspect of this invention, refers to bulkheads 10, 11, 12, 13 and 14 as vertical bulkheads. In point of fact, such a construction is the most expedient, and the bulkheads can easily be affixed by suitable means, such as rivets, bolts, screws, welding, etc. . . . or by any locking or interlocking device, to the beams 30, 31, 32, etc. . . .

Instead of affixing one single bulkhead, for instance, 13, 14, . . . to the corresponding beams 30—30a, 30b, 30c, 30d, etc. . . . the bulkhead may be affixed on both sides of these beams. This is illustrated on Figure 1 wherein a double-bulkhead 14₁—14₂ is composed of two separate walls affixed to both sides of the beams.

Single-bulkheads or double-bulkheads may be made of any kind of material—par example, sheet-iron, sheet-steel, armour plate, etc. . . . Where double-bulkheads are employed, as shown on Figure 1, 14₁—14₂, the free space between them may remain free, i. e., filled with air 54 or may be filled with shock-absorbing materials, such as wood 55, paper, sand 56, rubber 57, and the like.

If desired, the bulkheads may be placed not at

the sides of the beams, but between the said beams as shown in 14₃, Figure 1. In this case, either 14 and 14₃ are used simultaneously, or only 14, or only 14₃.

Instead of constructing the bulkheads 10, 11, 12, 13, 14 vertical in respect to the water-line, they can be made slightly inclined to the waterline, or even very strongly inclined as illustrated on Figure 6, wherein bulkheads 50, 51, correspond to 13 or 14 of Figure 1, and 52, 53 to 11 or 12 of Figure 1, dividing the ship into inclined safety-sections and having, as shown by way of example, a bulkhead top-line P₃—P₃ which provides a common partition of free air-space M₁. Should all inclined bulkheads extend from the upper deck U to the bottom K, as 52, then no common partition should be provided.

To facilitate the escape of gases from the safety-sections in which they explode, the surfaces of bulkheads 10, 11, 12, 13, 14 may be provided with a smooth surface, or may be polished, or covered with a smooth coat of paint or varnish.

The choice of the number of beams 30, 31, 32 and 19, 20, and the order in which they are placed between each of the two bulkheads, is a matter for the designer of the ship. It should be noted, merely, that such beams offer a very small resistance to the exploded gases because of their small surfaces and small volume.

If the torpedo explodes between 13—14 in "X" Figure 1, or in X₁ Figure 6, and should neither bulkhead 13 nor 14 in Figure 1, and 51 or 52 in Figure 6, be demolished, then the one-safety-section system is provided. Should the torpedo demolish one of the two bulkheads forming a safety section, then a two-safety-section system is provided.

In the event that the torpedo demolishes two neighboring bulkheads, then a three-safety-section system is provided, and so on.

This invention, as herein described, permits the application of any desirable number of these "safety-section-systems."

To assist and increase the efficiency of this method and construction, the upper or side surface of the common partition of the free air-space may be provided with a free opening, or free outlet into the atmosphere. Such opening may have automatically operated outlets or valve-like, pivoted trap-doors, or the like. One of the aspects of such outlet-system is shown schematically on Figures 1, 2, 3, 4 and 5 wherein the upper deck U is provided with a plurality of trap-doors which establish, when opened, a free passage for the exploding gases from the safety-section in which the torpedo or shell or mine explodes. Such trap-doors, 33, 34, 35, 36 may be arranged in a single row of a size approximately equal to the distance between the inner and outer hulls, as illustrated by 33 on Figures 1, 2 and 3. They can be placed one adjacent to the other or with spaces between them. Instead of a single row of trap-doors, two rows or more may be provided. To operate trap-doors, gear 42 is provided combined with a gear 43 and with worm-gear 44, said worm-gear being rigidly affixed to the shaft 45 provided with a lever 46 and a handle 47, and may be easily operated by one or two men of the crew. If desired, instead of the lever 46 and the handle 47, or in addition to them, a motor-driven arrangement may be provided, such as a steam-operating motor (generally employed on ships for the winding of cables) or an electric motor or a pulley to be operatively connected with a driving

shaft, or any suitable toothed arrangement which will enable a clockwise and counter-clockwise movement of the shaft.

The serrated member 41 may be pivotally attached to the trap-door 35 through the intermediary of a pivotal connection 48 provided in the element 49 rigidly affixed in respect to the trap-door.

In the double-row arrangement of trap-doors, two worm-gears 44 and 44₁, Figures 4 and 5, can be mounted on the same shaft 45.

The trap-doors may be made of any material, and if desired, they may be made of armour-plate steel so that if shells hit the trap-doors when they are opened or closed, the shells will bounce against the trap-door and glance off due to the fact that the trap-door when opened can be opened at an angle to the upper deck, as illustrated on Figure 4.

When in battle, or in the war zone, the trap doors should be opened on the side where the ship may be attacked, or for better precaution, on both sides of the ship. If there is fear only of mines, and the ship is going at a fair rate of speed, the trapdoors in the bow must be open so that the trap-door to each safety-section vulnerable to attack, is open.

Instead of operating the trap-doors by mechanical means, they may be simply pivotally attached or hinged through appropriate means so that they open only when the pressure in the safety-section and/or in the common partition of the free air-space of the exploded gases reaches such a degree that the trap-doors automatically lift and the exploded super-pressure gases are enabled escape into the atmosphere.

Instead of placing the pivot axis 40 parallel to the longitudinal line of the ship, said axis may be placed perpendicular to it, or at any required angle.

It should be noted that the cisterns for ballast, with their standard equipment, should be placed, as usual, i. e., between the inner-boards of the ship.

Another aspect of this invention consists in an appropriate choice of thickness of the outer board 21 and the thickness of the inner board 22 and of the distance between the two boards. In the majority of cases, it will be found advisable to make the outer board much thinner than the inner board.

The upper part of the outer board 21, i. e., that part which extends from the upper deck U, downwards to the water line or slightly below the water line, may be made of a hardened steel (bullet or torpedo proof), or armored steel; and the remaining part, i. e., the lower part of the outer board, extending downwards below the water line, can be made of carbon-iron alloy not necessarily hardened. If desired, the whole outer board may be made of torpedo-proof or armoured steel. For the upper part of the outer board 21 a hardened torpedo-proof or armored plate may be employed, having a thickness of 4 to 6 inches. This, however is given by way of example only, and does not limit the thickness of the boards to any appropriated dimension. The steel used in the lower part may be made of ordinary armour-plated steel of about 1 to 3 inches in thickness.

The inner board 22 can start from the very keel K of the ship as shown on Figure 3. If necessary, it may even follow the keel of the ship to a certain point, and may, for instance, be extended, as shown in dotted lines 37 on Figure 3.

The inner board 22 may be made from heavy

armor having a thickness of, for instance, 7, 10, 12 or more inches. The lower part of such inner board extending below the water line should preferably be made from unhardened steel, or from armor-plated steel that has not been especially subjected to hardening.

The distance Z (Figures 2 and 3) between the inner and outer boards is equal to the thickness of the safety-sections or to the thickness of the common partition of the free air-space M Figure 3 and may be between 5 to 12 feet. Owing to the fact that the battleship generally places itself with its bow to the enemy's fire, it will be advantageous to maintain the distance Z as wide as reasonably possible in the bow and stern of the ship also.

However, for a general construction, the Z in the middle part of the ship may be 7 to 15 feet, and towards the bow and stern, gradually diminishing from 4 to 8 feet.

Instead of a two-board system consisting of one outer and one inner board, a tri-board system may also be employed. For instance, the first outer board, may be at a distance of four or five feet from the second or middle board, and said second or middle board at a distance of five to seven feet from the third or inner board, as shown in Z and Z₁ on Figure 2. An appropriate choice of thickness of each of the said three boards and the choice of the distances Z and Z₁ between them, may vary in accordance with the construction of the ship and in accordance with the desirable degree of security to be provided against torpedoes, shells and mines. If properly chosen, even a two-board construction will offer the greatest security when built in accordance with the invention described herein.

Instead of three boards, four boards may be used. Z₁, Z₂ may be chosen accordingly, as well as the thicknesses of the respective boards.

When a three-board system is employed, such a system will have two independent and different groups of safety-sections and also two independent common partitions of free air-spaces M₁ and M₂.

When properly chosen, such a three-board system provided with sufficiently spacious M and M₁ and having suitable thicknesses of the first, middle and third boards, a suitable distance of Z and Z₁ will offer almost absolute safety for the ship against torpedoes, mines and the like. For a three-board system, by way of example, the thickness of the boards and the distances between them, may be made as follows:

	Thickness of board	Quality of steel	Distance between the boards
1st or outer board.	4 to 7" in upper part. 1 to 4" in lower part.	Preferably hardened. Not necessarily hardened.	From 4 to 15 feet or from 15 to 4 feet.
Middle board.	3 to 15" in upper part. 3 to 15" in lower part.	Hardened or unhardened.	
Third or inner board.	1 to 7" in upper part. 1 to 10" in lower part.		

A battleship costing, for example, from thirty to fifty millions of dollars, if provided with the board system, in accordance with this invention, will cost even less if constructed with the two-board system, and will, in addition, offer an incomparably greater, almost complete safety against torpedoes and the like, if the dimensions are properly chosen.

If such a battleship will employ a three-board system, provided with safety sections and preferably, also with one or two common partitions of free air-spaces, of the character referred to herein, they will offer substantially absolute safety against damaging means of any kind. Such construction may cost 3 to 5% more but this is relatively nothing when compared with the fact that this extra expenditure permanently insures the safety of the ship and the lives of those on board.

This invention is not limited to the figures stated herein with reference to the thicknesses of the boards the distances Z or Z₁ between them, but may be of any other suitable or expedient thickness or distance.

The same construction as described herein, for battleships, etc., can be employed in the building of submarines, in which case, the ballast cistern system should be placed in between the inner and outer boards, but inwardly in respect to the inner board, i. e., between the left and right inner boards. A second inner board may be provided, if desired, and in such case, a ballast cistern system should be placed between the first inner and the second inner boards.

Having now particularly described and ascertained the nature of the herein described invention, and in what manner the same is to be used, I declare that what I claim is the following:

1. An armored ship having at least three decks and having a hull structure comprising an inner wall and an outer wall spaced from the inner wall to provide a free air space between said walls, said free air space being unobstructed by horizontal partitions or bulkheads and extending substantially the bottom of said ship to the first deck thereof, a plurality of vertical bulkheads dividing the lower portion of said free air space into separate safety compartments, each of said vertical bulkheads extending from the bottom of said air space to a point at least as high as the third deck, each of said safety compartments being open at the top for communication with the undivided upper portion of said free air space, a plurality of beams extending between said inner and outer walls and holding said walls rigidly in mutually spaced relation.

2. An armored ship having at least three decks and having a hull structure comprising an inner wall and an outer wall spaced from the inner wall to provide a free air space between said walls, said free air space being unobstructed by horizontal partitions or bulkheads and extending from substantially the bottom of said ship to the first deck thereof, a plurality of vertical bulkheads dividing the lower portion of said free air space into separate safety compartments, each of said vertical bulkheads extending from the bottom of said air space to a point at least as high as the third deck, each of said safety compartments being open at the top for communication with the undivided upper portion of said free air space, a plurality of beams extending between said inner and outer walls and holding said walls rigidly in mutually spaced relation, a plurality of trap doors communicating with said safety compartments being provided in the said upper deck.

3. An armored ship having at least three decks and having a hull structure comprising an inner wall and an outer wall spaced from the inner wall to provide a free air space between said walls, said free air space being unobstructed by horizontal partitions or bulkheads and extending from substantially the bottom of said ship to the

first deck thereof, a plurality of vertical bulkheads dividing the lower portion of said free air space into separate safety compartments, each of said vertical bulkheads extending from the bottom of said air space to a point at least as high as the third deck but not higher than the second deck, each of said safety compartments being open at the top for communication with the undivided upper portion of said free air space, a plurality of horizontal beams extending between said inner and outer walls and holding said walls rigidly in mutually spaced relation.

4. An armored ship having at least three decks and a hull structure, comprising an inner wall and an outer wall spaced from the inner wall to provide a free air space between said walls, said free air space being unobstructed by horizontal partitions or bulkheads and extending from substantially the bottom of said ship to the first deck thereof, a plurality of vertical bulkheads dividing the lower portion of said free air space into separate compartments, each of said vertical bulkheads extending from the bottom of said air space to a point at least as high as the third deck, but not higher than the second deck, each of said safety compartments being open at the top for communication with the undivided upper portion of said free air space, a plurality of horizontal beams extending between said inner and outer walls and holding said walls rigidly in mutually spaced relation, a plurality of trap doors communicating with said safety compartments being provided in the said upper deck.

5. An armored ship as set forth in claim 3

wherein said trap doors are made of armored plate.

6. An armored ship as set forth in claim 3 wherein said trap doors are armored, means being provided to operate the opening and closing of said trap door.

7. An armored ship having at least three decks and having a hull structure comprising an inner wall and an outer wall spaced from the inner wall to provide a free air space between said walls, said free air space being unobstructed by horizontal partitions or bulkheads and extending from substantially the bottom of said ship to the first deck thereof, a plurality of vertical bulkheads dividing the lower portion of said free air space into separate safety compartments, each of said vertical bulkheads extending from the bottom of said air space to a point at least as high as the third deck but not higher than the second deck, each of said safety compartments being open at the top for communication with the undivided upper portion of said free air space, a plurality of beams extending between said inner and outer walls and holding said walls rigidly in mutually spaced relation, a plurality of trap doors communicating with said safety compartments being provided in the said upper deck, said inner wall being made from thick armor at that part thereof which is within torpedo range, the said outer wall being made of as thin as possible armor at that part thereof which is within torpedo range.

ALEXANDER D. MASLOFF.
